(57) **CLAIM**

The ornamental design for an adult toy, as shown and described.

DESCRIPTION

FIG. 1 is a perspective view of an adult toy showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the adult toy, shown in an exploded configuration; and,

FIG. 10 is a perspective view of the adult toy, shown in another exploded configuration.

The dash-dash broken lines in the drawings depict portions of the adult toy that form no part of the claimed design.
